UNITED STATES PATENT OFFICE.

HARRY SPURRIER, OF CHICAGO, ILLINOIS.

METHOD OF TREATING CERAMIC MIXTURES.

No Drawing.

Application filed January 24, 1924. Serial No. 688,351.

To all whom it may concern:

Be it known that I, HARRY SPURRIER, a subject of the King of Great Britain and Ireland, and a resident of Chicago, in the county of Cook and State of Illinois, have invented certain new and useful Improvements in Methods of Treating Ceramic Mixtures, of which the following is a specification.

10 This invention relates to improvements in methods of treating ceramic mixtures and more especially to the treatment of bodies, notably of a plastic or porous character, and used commercially for the manufacture of pottery, crucibles, tile and stone ware, spark plugs, and the like.

The object of the invention is to provide an improved and more efficient method of rendering the body or plastic mass less 20 vesicular, that is to say, of decreased porosity by the removal of the air or gas content of the mass which is inherent therein.

It is well known in the ceramic art that it is desirable, if not essential that the mass 25 be gas and air free, in order that the resulting product shall be useful for the purpose intended.

I am not aware of any method heretofore developed or in use at the present time 30 which has successfully accomplished the result contemplated by the method herein described.

While it is possible to accomplish the desired end in various ways, I have discovered that the following is the most effective and therefore is to be preferred.

In describing the process it is to be understood that the term mass or body contemplates any and all plastic or porous substances of which clay mixed perhaps with other ingredients, is a suitable example. Considering then a mass of clay in plastic state it is a fact that it has gases disseminated throughout and which assume the 40 form of globules, some minute and others of substantial size, depending on the circumstances and conditions of the mass. The problem therefore is to remove these gases and I have therefore resorted to a process 45 consisting of subjecting the mass to reduced air pressure, commonly conceived to be a vacuum.

This air pressure reduction or the step termed evacuating the gases from the mass, 55 may be readily accomplished by introducing the mass to be treated into a suitable air-

tight chamber, having communication with an air exhausting apparatus such as an air pump and provided with one or more valved openings of a size to permit of a rapid inrush of air into the chamber when opened. By the action of the air pump, the air is exhausted as completely as possible not only from the space (if any) surrounding the mass, but from the mass itself. 65

Having thus exhausted the gases from the mass by the creation of the vacuum or condition of reduced air pressure, the vacuity is broken suddenly by opening the inlets to the chamber so that the increase in pressure 70 shall be as rapid as possible.

Assuming that the inlets to the chamber communicate direct with the atmosphere, the pressure within the chamber is thus increased or restored to atmospheric pressure 75 with a suddenness that results in the subjection of the mass to the attending impact which restores the same to its initial condition, with the exception that the gases have been completely removed. 80

It is to be understood that in the practical application of the process certain conditions may make it preferable to restore the pressure within the chamber to that of the atmosphere, whereas under other conditions better results may be obtained by introducing a pressure greater than atmospheric in the chamber after the evacuation has been completed. In the latter instance any suitable means would be employed for 85 supplying the increased air pressure to the chamber.

Having described the purpose, method of carrying out and results to be obtained by my process, I claim as my invention: 95

1. The process of treating ceramic mixtures consisting of evacuating the gases from the mass, and suddenly breaking the vacuum. 100

2. The process of treating ceramic masses consisting of evacuating the gases from the mass, and suddenly subjecting the mass to a pressure equal to or greater than that of the atmosphere. 105

3. The process of treating ceramic materials consisting of evacuating a chamber containing a mass of the material and suddenly breaking the vacuum, while the mass is in the chamber. 110

4. The process of treating ceramic materials consisting of introducing a mass of the material into a chamber, subjecting the

chamber to a relatively high vacuum and suddenly restoring the pressure within the chamber to substantially atmospheric pressure.

5. The process of treating ceramic materials consisting of introducing the material into a chamber, evacuating the gases in the chamber to a relatively high degree of va-

cuity, and suddenly breaking the vacuum, without removing the material from the chamber.

In witness whereof, I hereunto subscribe my name this 22nd day of January, A. D., 1924.

HARRY SPURRIER.
